UNITED STATES PATENT OFFICE.

ALOYS LEHMANN, OF DUBUQUE, IOWA.

ARTICLE OF FURNITURE.

SPECIFICATION forming part of Letters Patent No. 735,277, dated August 4, 1903.

Application filed February 24, 1903. Serial No. 144,621. (No model.)

To all whom it may concern:

Be it known that I, ALOYS LEHMANN, a citizen of the United States of America, and a resident of the city and county of Dubuque 5 and State of Iowa, have invented certain new and useful Improvements in Articles of Furniture, of which the following is a specification.

My invention relates to cabinet furniture, 10 with special reference to such as is used in kitchen and dining-rooms; and the object is to supply to housekeepers a cabinet which shall be simple in construction, occupy small space, and still provide numerous conveniences for housekeeping in a limited manner.

For a better understanding of my device 15 attention is called to the following specification, which gives a detailed description of the mode of construction and manner of use 20 when considered in connection with the drawings accompanying the same and forming a part hereof.

Figure 1 is a front view. Fig. 2 is a vertical section with the contents of the lower section 25 drawn out. Fig. 3 is the same view as Fig. 2 when the table and seats have been shoved partly in. Fig. 4 is a plan view looking upward from line X X of Fig. 1 when the sink has been drawn out. Fig. 5 is the same 30 view as Fig. 4 looking downward. Fig. 6 is a cross-section of the table and sink, and Fig. 7 is a detail of one of the seats and mode of attachment to the frame.

Similar numerals of reference refer to similar parts in each of the figures of the drawings.

Referring to the drawings, 2 designates the cabinet, which is divided into two parts or sections 4 and 5. The part 4 is removable and is provided with an ornamental cornice 40 6 and doors 8. In this section may also be shelves or partitions 10, which divide it into numerous compartments wherein may be placed chinaware, table-linen, or other necessary articles. In the lower part of this section 4 is an open space 12 for sideboard use and may be provided with a mirror in the rear. The base 14 of section 4 extends out beyond the upright part and over section 5.

Section 5 consists of a rectangular box in- 45 closed on the sides and partly open in front at 15 and supplied with feet 18. Within this

section, near the top, is located a rectangular-shaped sink 20, adapted to slide on ways 22, secured to the sides of the section. To the forward end of the sink are attached legs 21, 55 which support the sink when drawn out. Near the top of the sink on each of its inner sides is a groove or channel guide 25 for the purposes presently to appear. For the purpose of controlling the movements of the sink 60 there is pivoted to its base 26 an extension-rack 27, consisting of bars 28, which cross each other in pairs and are pivoted with a pivot-pin 29 at their centers and at their outer ends are also pivoted by a pivot-pin 65 30. Against the rear of the section 5 is rigidly fastened a bracket 32, which extends out and is bent at right angles and passes up through the rack 26 at 34 and is supplied with a nut 35. By this means the rack is 70 pivoted to the bracket-arm. In the base of the sink 20 is a groove or guide 36, and the pivot-pin at 29 passes through the bars and engages with the guide and travels therein and directs its movements. It will be seen 75 that when the sink is drawn out the rack is extended until it is stopped by bracket 32.

Over the sink 20 is a sliding table 38, to which is attached against its under surface, near its outer longitudinal edges, cleats 39, 80 which extend downwardly and are provided on their lower ends with tenons 40, adapted to engage the guides 25 in the sides of the sink and travel therein. In this manner the table cannot be lifted up from the sink, but 85 can slide thereon. The forward ends of the cleats 40 will engage with the legs 21 of the sink, and by this means the sink is drawn out by drawing the table out, and the table cannot be drawn farther than the end of the sink; 90 but the table can be shoved back in without movement of the sink.

Beneath the sink is a sliding frame 42, provided with legs or casters 44. On the bars of this frame are pivoted stools or seats 45 and 46 by pivot-pins 47. In order that the stools may be closed in to the base of section 5, there is pivotally attached to the side bars of the frame an arm 48, one at each side. These arms are provided with a shoulder 53, 100 adapted to engage the shoulder 50 in the arm 48. In this manner the seat 52 may be turned

on its pivot-pin 47 within the frame, and then the seat may be doubled over in front on its hinge or pivot-pin 49, and when so turned it can be closed into the section 5 when the 5 fame 42 is pushed into the section.

The front seat 46 is pivoted to the front edge of the frame 42 by securing arms 55 to the frame and uniting them together at their outer ends, to which the arm 48 is pivoted by 10 the pivot-pin 47. The seat 46 is also hinged or pivoted at 51 and is adapted to be turned over in the manner shown in Fig. 2. In this manner the seat 46, as well as the other seat 45, may be closed into the section 5 in the 15 frame 42 and when drawn out can be turned so as to permit them to be used as seats by parties using the table or the sink. To the rear of the frame 42 and table 38 is secured one or more bars 56, so that whenever the table is drawn out the seats will also be drawn out. It is manifest that the bars 56 may be dispensed with and an ordinary handle may be attached to the frame 42 for operating the frame to draw out and close in the seats. 20

25 A convenient way of operating my device is substantially as follows: Starting with the cabinet closed, as represented in Fig. 1, the operator grasps the table 38, draws it out, and the engagement of the cleats 40 with legs 30 21 will also draw out the sink, and with it the frame carrying the seats 45 and 46, by the connection of the rods 56 with the table. Then the doors 8 may be opened, and from the compartments in section 4 may be taken 35 a table-cloth and dishes to be spread upon the table 38. The seats are then turned outwardly and rest in convenient position for seats upon two sides and front of the table. When the table has been used, it may be

shoved back into section 5 and the dishes 40 placed in the sink for washing.

It will be seen that this article of furniture will occupy but a small space and still have numerous conveniences that are necessary for small housekeeping. 45

Having now described my invention, what I claim, and desire to secure by Letters Patent, is—

1. An article of furniture composed of two sections, an upper section provided with doors 50 and compartments therein, a lower section with a sliding sink, a sliding table above the sink, a sliding frame below the sink, arms pivoted to the frame, seats pivoted to the arms and adapted to fold over upon the arms 55 whereby the seats may be adapted to project out from the frame when the frame is drawn out and be folded together to be inclosed within the section when the frame is closed into the section. 60

2. An article of furniture consisting of an upper section provided with doors and compartments therein, a lower section having a sliding sink, a bracket attached to the section, a rack pivoted to the bracket and to the 65 base of the sink, a sliding table upon the sink, a sliding frame beneath the sink provided with legs, arms pivoted to the frame, seats pivoted to the arms and adapted to fold upon the arms whereby they may be folded over 70 and then inclosed in the section.

Signed at Dubuque this 12th day of February, 1903.

ALOYS LEHMANN.
